SIGNALING APPARATUS FOR HANDLING CODED INFORMATION Ralph V. Anderson, 2509 32nd St. SE.,
Washington 20, D.C.

Filed Feb. 12, 1954, Ser. No. 410,054

4 Claims. (Cl. 340—324)

(Granted under Title 35, U.S. Code (1952), sec. 266)

The invention described herein may be manufactured and used by or for the Government of the United States of America for governmental purposes without the payment of any royalties thereon or therefor.

This invention relates to a signaling method and apparatus for handling coded or other intangible information or intelligence in order to exercise a check or control over it. In the preparation of cryptographic aids of the "scrambled alphabet" type for instance, all predetermined letters, numerals or other symbols, hereinafter called characters, are used to form a section of a cryptograph. While all the characters must be present in each section they are "scrambled" and their sequence varies with each section in accordance with their varying meanings. If any one character in a particular section is omitted and another character erroneously repeated instead, such a section is defective. Up until the present invention a manual method of control and error elimination has been employed, the controller laboriously checking on a sample list containing all the predetermined characters, the occurrence of each character in the section checked to elicit an omission of one character and the repetition of another character for it.

An object of the present invention is to provide a simple, quick and efficient mechanical system of check or control of coded information or other intangible intelligence by utilizing typographical skill of a typist of conventional training.

Another object is to provide a check of coded information through visual illustration by a device comprising a keyboard similar to that of a typewriter with each key actuating a corresponding signal control light on a control panel board to indicate the occurrence or absence of a character and with each key also actuating a second signal light preferably common to the whole keyboard, to indicate an erroneous duplication of a character in the section of the cryptograph checked.

A further object of this invention is to provide a single typewriter-like machine for the purposes described, having the necessary operating elements arranged in the manner conventional to a typewriter to perform however non-typing functions specific to the handling of coded information and to the signaling of errors, to enable a typist of average skill and intelligence to operate it efficiently and accurately in the conventional typing manner without additional training.

Another object of the invention is to provide a signaling system for the purposes described comprising a typewriter-like keyboard, in which each key, when depressed is connected through an electrical switch with a separate relay and with a separate signal lamp and in which each key in addition also is connected with a universal switch, two relays and two light signals common to all keys, and a relay selecting mechanism, which upon the completion of the typing of a section selects the separate relays not energized, if any, to signal the omission of a

2

character, and which selects the error relay, if energized, to signal the duplication of a character.

Another object of the invention is to provide a duplication detecting and indicating mechanism for the purposes described comprising electric input actuating means connected to produce a second separate signal upon repetition of the same electric input.

Another object of the invention is to provide a duplication detecting and indicating mechanism for the purpose described, comprising a plurality of keys, each upon first depression closing an individual circuit to produce an individual signal reserved for and corresponding to the particular key depressed, each key upon first depression simultaneously also energizing a secondary circuit, common to all keys, to produce a second separate signal upon duplication of the depression of the same key.

Other objects of the invention will become apparent by reference to the following specification and accompanying drawings.

20 Fig. 1 is a perspective view of the signaling apparatus of the present invention.

Fig. 2 is a diagrammatic representation of a basic example of a circuit of the invention.

25 Fig. 3 is a diagrammatic view of a portion of an electric circuit demonstrating a preferred embodiment of the circuitry of the apparatus.

Similar characters of reference indicate similar or identical elements throughout the specification and drawings.

30 In the drawings: the signal apparatus is represented by a housing 9, preferably of the shape and dimensions of a conventional typewriter and is equipped with a conventional keyboard 12, exhibiting a plurality of key levers, 13, in four rows, and an error signal bar 15, hereinafter called the signal bar, at the bottom of the keyboard and resembling there the conventional "space-bar" of a typewriter. There also is present a pair of key levers, one on the left hand side, and one on the right hand side indicated as L Rel and R Rel and hereinafter called release keys. These occupy the same positions as the shift keys of a typewriter. All the character key levers, hereinafter will be called "keys." The keys depress upon the conventional touch of a touch-typist, so does the signal bar and the release keys.

45 40 While any combination of characters may be employed, which is desirable for the particular cryptographic or other system used, be it assumed that the apparatus of the present invention in the embodiment shown, employs twenty-six letters, ten numerals, and one dash, altogether thirty-seven characters, and that they occupy positions corresponding to those of the American conventional typewriter keyboard.

45 55 The diagrammatic circuitry of Fig. 3, for the purposes of simplicity, demonstrates a detail of electrical connections of only four keys out of the identical connections of the thirty-seven keys present, the rest of the circuit, the space bar and the pair of release keys being common to all the thirty-seven keys. Therefore the circuitry hereinafter will be explained with reference to four keys only at random selected as characters A, B, C, D, as representative of the thirty-seven keys present. Each key has assigned to it a corresponding individual switch such as 18, with the associated circuitry described hereinafter. In addition to operating its individual switch each key also operates through mechanical connections a universal switch 26, common to all keys, which closes after the depression of any key 13. On the top of housing 9, in the space occupied in a conventional typewriter by the paper typed on, is a signal panel 10, comprising four rows spaced in parallel and corresponding to the four rows of the key board and exhibiting thirty-seven signal

light windows 11, at an angle to horizontal allowing their quick simultaneous observation by the typist. The signal light windows correspond to the characters of the key board and they are spaced on the signal board in the same sequence and order as the keyboard characters. The two keys in the front row, that is the second and third from right, have no function except to keep the keyboard familiar to the typist and serve as finger rests. An additional larger error signal window 14 hereinafter called "double window" in the right front corner of the signal panel is common to all keys. Each window on the panel houses a signal light bulb, such as LA, LB, LC and LD and the double window 14 has two bulbs L14 for greater conspicuity. The signal light of the double window is actuated by the erroneous double depression of any one of the character keys. The electrical circuit comprises a relay bank of thirty-seven relays, such as AR, BR, CR and DR, each individually assigned to one of the corresponding thirty-seven character keys respectively, a relay selecting mechanism of two relays, L Rel and RL, and a current input 22 and 23. A basic circuit is demonstrated in Fig. 2. Three A.C. relays A, Y and Z of predetermined resistance, such as 850 ohms, are provided with two sets of switches functioning as breakers 29 and 25 with one universal switch 26 functioning as a circuit maker. Resistance R1, such as 1000 ohms, is provided in the circuit to withstand the flow of current through it when input through 22 and 23 will be applied across it. The several relays each has contacts, numbered from 1-6 as shown and thus hereinafter for the purposes of clarity the word contacts refers not to the switches 26, 25 and 29 but to the contacts 1 to 6 of the various relays only.

The circuit of Fig. 2 is so arranged that the first time the circuit is closed by switch 26, the Y relay will be energized closing its contacts 5 and 6 which in turn supply current to relay A. Although current is supplied to relay Z through contacts 1 and 2 of relay Y, the operating action of relay Y is sufficiently fast to break its contacts 1 and 2, leaving relay Z unaffected.

The A relay armature, when pulled down, closes contacts 5 and 6, locking itself. Upon release of switch 26, the armature of relay Y restores itself to normal, current is supplied to its contact 5 through the locked position of contact 6 of relay A. Contact 4 of relay Y is connected to the relay coil magnet Y supplying potential to this terminal. When switch 26 is now operated for the second time relay Y can not operate because the same potential is supplied to both terminals of the magnet coil. Current is thus supplied through contacts 1 and 2 of relay Y to relay Z. Relay Z will be energized and will lock itself through its contacts 5 and 6. Switch 29 will release A and switch 25 will release Z. The connection from contact 3 of relay Z to the juncture of relay Y terminal and resistance R1 prevents relay Y from vibrating. Transformer T and signal light LA are added to contacts 2 and 3 of relay A for visual indication of its condition. Signal light LA is representative of all thirty-seven signal lights and their connections are shown in greater detail in Fig. 3. Double error signal light shown as "double" L14 connected with resistor R2 to the contacts 2 and 3 of relay Z is included to indicate the condition of the relay Z. The Z relay is common to all thirty-seven character keys.

The universal switch 26 is common to all thirty-seven keys. The keys each have an angle lever with a short vertical bar carrying the character button and with an elongated horizontal bar comprising actual linkage with switches 18 to 21. All the horizontal bars are spaced at the bottom of the housing at one level. The universal switch 26 in Figs. 2 and 3 is indicated by dotted lines as leading to 26. The bar is positioned horizontally underneath the horizontal bars of the character keys and at 90° angle to them. The depression of a character key, such as A, operates first the corresponding character

switch 18 and immediately thereafter the universal switch 26.

In Fig. 3 the theory of the circuitry shown in Fig. 2 is applied to a preferred embodiment of the apparatus exhibited in Fig. 1 and shows the complete circuit for four of the thirty-seven characters. The relays AR, BR, CR and DR with light signals LA, LB, LC and LD with associated circuitry are taking place of the single relay A and light signal LA respectively. The circuitry of the double error signal light L14, of the right release switch 29, of the left release switch 25, of the universal switch 26, and of the relays Y and Z remain unchanged. Switch 27 is included to be operated by the error signal bar 15. The function of the circuit of Fig. 3 is as follows: The key A on the keyboard, when depressed, closes its corresponding switch 18. Immediately thereafter the universal switch 26 closes and current is supplied to relay Y. The operation of relay Y through its contact 6 to contact 5 and over switch A energizes relay A, which locks itself and primes the circuit to light signal LA. LA will not light however until the transformer T1 will be energized. The release of key A opens switches 18 and 26, and relay Y will return to its normal position. If however, by error, key A is depressed the second time, relay A through switch 18 supplies current to the terminal magnet coil Y by means of Y's contacts 4 and 5. The closing of switch 26 applies a potential to relay Z through contacts 1 and 2 of relay Y, relay Z will become energized and locked. By locking of relay Z a potential is applied through contacts 2 and 3 to the double signal light L14 and to the resistor R2 and L14 will signal. Two bulbs are used to increase the intensity of the double signal light over the character signals.

Thus during a normal operating procedure the typist depresses the character keys corresponding to the characters of the coded section to be checked, depresses the error signal bar 15 to read the results, and then depresses the left release key 25 to unlock all character relays for the next operation. If after depression of one of the character keys the double signal L14 flashes, the typist will stop to check that particular character, will release the double signal light by pressing the right release key 29, and will then proceed to the next character. Upon completion of an erroneous section one character signal will not light showing that it has been omitted, since one other character has been repeated erroneously instead.

Many modifications and variations of the present invention are possible in the light of the above disclosure. It is to be understood that within the scope of the appended claims the invention may be practiced otherwise than as specifically described.

What is claimed is:

1. A signaling apparatus for handling of intelligence in sections defined by a predetermined number of different characters, to exercise an omission and duplication check over each of said sections separately, comprising a keyboard provided with a character key for every said character and with at least one control key, an error signal release key, and a character release key, a signal panel positioned for visual observation during typing, said signal panel having a plurality of individual signal means, one for each said character key, spaced on said signal panel, error signal means common to all said character keys, linking means between each said character key, its respective signal means and said error signal means, connected to put into readiness the character signal upon a first depression of said character key, linking means between each said character key and said error signal means connected to actuate said error signal means upon a second depression of a said character key, error signal release means connected to erase the error signal upon depression, character signal means connected with said control key to actuate the said character signals brought into readiness by the first depressions of said

character keys upon the depression of said control key and means connected to cancel the said readiness of said character signals upon depression of said character release key.

2. A signaling apparatus for handling and checking character sequences as in claim 1 wherein said apparatus operates on an electric current input, the said keys function as electric switches, the said signal means are electric light bulbs and the said linking means are an electrical circuit.

3. A signaling apparatus for handling of intelligence in sections defined by a predetermined number of different characters, to exercise an omission and repetition check over each section separately, comprising a touch type keyboard provided with a character key for every said character, with a control key for said repetition check, with a character release key and with an error signal release key, a signal panel positioned for visual observation during typing and provided with a signal light window and light bulb for every said character key and spaced on said signal panel in a sequence and order corresponding to the sequence and order of the corresponding keys on the keyboard and with an error signal light window and error-signal-light-bulb, an electric current input, a plurality of individual character circuitries each corresponding and connected with one said character key and each including a character switch, a character relay connected to said character switch on depression of said character key and a character light bulb primed to produce a corresponding character signal on said panel upon the depression of its character key and actuated upon the subsequent depression of said error signal key, a universal circuitry, including a universal switch, a universal relay connected to said universal switch and energized upon actuation of said universal switch, an error relay, and an error signal bulb common to all character circuitries and connected with them, said error relay connected automatically to close said error signal bulb upon two depressions of a character key, said control key operating a separate control switch connected to close the character circuits when primed by the first depression of a character key to light said character signal bulbs on said panel board, said error signal release key being connected with the circuitry to release upon depression said error signal, said character release key being connected with the circuitry to release upon depression the character relays.

4. A signaling apparatus for handling intelligence in sections defined by a predetermined number of different characters to exercise an omission and repetition check over each section separately, comprising in combination: a touch-type keyboard provided with character keys and

character switches, one each said character key and character switch for every said character and with one universal switch, common to all said character keys, each said character key having means to close upon its depression its respective said character switch and thereafter to close said universal switch; a character switch circuitry, one for each said character, including a character relay and a character signal light; a universal switch circuitry, including a universal relay; an error signal release key with circuitry including an error signal release switch, an error relay and a double error signal light, a character signal bar with circuitry including a control switch and a transformer; and a character release key with circuitry including a character switch; said keys each connected to operate upon its depression its respective switch; an electric input terminal with power means for energizing said circuitries; a signal panel positioned for visual observation during typing and provided with a signal window for every said character signal light and one window for said double error signal light, said windows spaced on said panel in a sequence corresponding to that of said characters on said keyboard; means to connect in sequence upon a first depression of any of said character keys said character switch, said universal switch, said universal relay and said character relay to prime the corresponding said character signal light, means to disconnect said universal relay upon a first release of said character key, means to connect upon a second depression of the same said character key, in sequence, said corresponding character switch, said character relay and said universal relay and thereafter said universal switch with said universal relay to connect said error relay to actuate said double error light; means to connect upon a depression of said error signal release key, in sequence, said error signal release switch and said error signal relay to turn this latter relay inoperative and to cancel said double error signal light; means to connect upon a depression of said character signal bar said control switch and said transformer, to actuate simultaneously every said signal light primed by said first depression, means to turn off all said actuated signal lights upon a release of said signal bar; and means to connect upon a depression of said character release key said character release switch to make all character relays inoperative.
